ROBERT S. LAUGHLIN, OF PORTLAND, MAINE, ASSIGNOR TO THE THOMAS LAUGHLIN CO., OF PORTLAND, MAINE, A CORPORATION OF MAINE.

SPLIT LINK FOR CHAINS.

1,118,657.

Specification of Letters Patent. Patented Nov. 24, 1914.

Application filed May 6, 1914. Serial No. 836,804.

To all whom it may concern:

Be it known that I, ROBERT S. LAUGHLIN, a citizen of the United States, residing at Portland, in the county of Cumberland and 5 State of Maine, have invented certain new and useful Improvements in Split Links for Chains, of which the following is a specification, reference being had therein to the accompanying drawing.

10 This invention relates to an improvement in what is now commonly known as split links for chains, and the same relates to that particular type of link shown and described in the patent to W. J. Laughlin No. 774189, dated November 8, 1904. In the construction of link shown in said patent, provisions are made to take the strain from the rivets and preventing the ends of the tapered portions from spreading or straightening out.

15 This construction has been found to be very useful and highly efficient, but for certain types of link it has been found, in practice, that certain torsional strains occur which have a tendency to loosen the connections of 20 the parts. To overcome this objection is the purpose of the present invention.

In the accompanying drawings: Figure 1 represents a plan of one section of the link, it being understood that the two sections 25 are identical; Fig. 2 is a side elevation; Fig. 3 is a plan view of the link sections secured together; Fig. 4 is a section on the line 4—4 of Fig. 3; and Fig. 5 is a section on the line 5—5 of Fig. 3.

30 It is to be understood that while the preferred form of link is shown in the accompanying drawings, the special arrangement and specific construction there illustrated may be modified and changed within the 35 scope of the appended claim without departing from the spirit of the invention.

A and B represent the two parts of the split link made as above stated alike. These parts represent a solid sectional portion, 40 substantially cylindrical, although other forms may be resorted to if desired. On each side of the center portion are split end portions a , c^2 , through the extreme ends of which are formed perforations a^3 . Adjacent the body or central portion are the outstanding pins or rivets b . This structure is

conveniently formed of malleable iron so that the parts may be formed by drop forging, if desired. Formed on the flat faces of the split portions of the link member on opposite sides of the center of the end portions are upwardly projecting teeth C . These teeth are conveniently rectangular in cross section, tapered on one side and having a substantially straight opposite side. 55 They project a slight distance above the plane of the surface of the split end portion of the link. Immediately adjacent the teeth and on the side of the straight face thereof are the sockets e in shape corresponding substantially with the shape of the teeth. These teeth and depressions are arranged radially of the center of the link so that when the parts are assembled the tooth or projection on one link will fit the recess 60 on the other and thereby form a positive interlock between the parts so positioned as to resist throughout their flat contacting surfaces the torsional strains which would tend to cause the split portions of the link members to become distorted and the riveted connections broken or cracked. By positioning the interlocking parts on opposite sides of the center of the ends of the split members and arranging them substantially in a radial line with the center, a structure is 65 formed which has very great strength and will when assembled, represent a link of a strength equal to that of a solid structure. The projections being located adjacent the 70 ends of the split members also serve to strengthen materially the connection between the members.

75 While it has been suggested that these links can be made by drop forging, in which particular it has been found most satisfactory, yet it will be understood that they can be produced by other methods if desired. After the links and parts have been assembled the ends of the rivets or pins are upset 80 as in the ordinary manner.

Having now particularly described my invention, what I desire to claim as new and secure by Letters Patent is:

85 The herein-described split link composed 90 of two link parts each of which has one solid side and split tapered ends, the tapered ends 95

at their thickened portions where they adjoin the solid sides having rivets projecting therefrom, and the opposite portions of said ends being provided with openings for receiving the rivets of the companion member, the tapered ends of each link part being also provided at points at opposite sides of the center thereof with a tooth and a receiving

socket for the companion tooth of the other link part, substantially as described. 10

In testimony whereof I hereunto affix my signature in the presence of two witnesses.

ROBERT S. LAUGHLIN.
